DECORATIVE WALL COVERING

Gaston Desagnat, New York, N. Y.

Application February 12, 1941, Serial No. 378,589

4 Claims. (Cl. 72—22)

The present invention relates primarily to wall or other surface covering of the type comprising hard or rigid decorative facing material such as glass, tile, marble, porcelain or the like, for plane or curved surfaces, whether concave or convex, for instance, walls, ceilings and like plane or curved interior or exterior surfaces.

Among the objects of the invention are to provide a durable covering of the above type, which shall be highly ornamental in appearance, and which may be fabricated and installed at small expense.

Another object is to provide a covering of the character referred to, which includes a supporting or backing fabric that readily conforms to irregularities in the wall structure without detachment thereof from the rigid facing.

Another object is to provide such covering, the backing of which admits of relative displacement longitudinally and transversely for adaptation to irregularities in the wall and to effect proper registry, which displacement may be of magnitude considerably greater than the inherent distendability of the backing fabric itself.

The invention in the various embodiments disclosed in the present application is concerned essentially with modifications or variants of the subject matter of my prior Patent No. 1,930,740 of October 17, 1933, reissued under No. 21,313 on January 2, 1940; and of my prior Patent No. 1,976,986 of October 16, 1934, reissued under No. 21,285 on December 5, 1939.

In the accompanying drawing in which are shown one or more of various possible embodiments of the several features of the invention:

Fig. 1 is a perspective view on an enlarged scale showing the corner of one embodiment of the invention, part of the hard facing being shown broken away more clearly to disclose the structure of the backing material.

Fig. 2 is a fragmentary transverse sectional view on a larger scale, along the line 2—2 of Fig. 1, showing the wall covering in installed relation.

Fig. 3 is a perspective view of the rear face of the decorative wall covering with an alternating form of backing.

Fig. 4 is an enlarged fragmentary detail in section on line 4—4 of Fig. 3.

Fig. 5 is a view similar to Fig. 4, showing the distension of the covering, and resultant separation of the facing blocks.

Fig. 6 is a fragmentary rear perspective view of the embodiment of Fig. 3 showing the manner in which the distension of Fig. 5 occurs.

Fig. 7 is a rear perspective view with parts broken away, showing a modified form of the invention.

Fig. 8 is a sectional view showing one step in the method of preparing the embodiment of Fig. 7.

Fig. 9 is a perspective view showing a further step in said method, and

Fig. 10 is a fragmentary sectional view showing the embodiment of Figs. 7 to 9 installed.

Referring now to the drawing, there is shown in Figs. 1 and 2 covering material involving a decorative rigid plate 10 of glass or the like prepared as an article of manufacture, with a backing of a particular material characterized by low cost, softness and felting properties and especially useful in mounting panels of the prepared decorative article, such as glass upon wall structures that may not be absolutely plane but may present minute waves or irregularities.

The inexpensive fabric is ribbed in character and comprises a set of parallel relatively thicker untwisted strands 11 which may be of inexpensive short-fiber cotton or the like with a series of 15 relatively thin transverse threads or strands 12 interwoven thereacross.

The decorative rigid cover plate 10 is adhesively secured to the face of the backing, preferably by means of a coating of water soluble glue. 20 Desirably, this glue is a mixture in an aqueous carrier of casein and a filler that imparts a porous character to the dried glue, the degree of porosity depending upon the proportion of filler used. The filler is desirably calcium carbonate, 25 but other fillers such as lithopone, titanium oxide, clay and the like may be utilized to advantage.

The glue is brushed or spread upon the back of the glass or other rigid covering material, whereupon the fabric is laid over it and then the assembly is dried, desirably in an oven at about 120 degrees C. for about one hour. In the gluing operation, the water solvent of the glue may penetrate by capillary action through the fabric backing, but the adhesive ingredient by reason of its colloidal nature, will effectively be retained substantially at the outer face of the backing and in contact with the rigid covering. 30 The water wetting through the backing will readily evaporate in the drying oven to leave said backing clean, dry, soft, supple and capillary, thereby to present a large surface for bonding thereto of the mastic 14 used for applying said backing to wall W, for effecting secure attachment. Mastic of conventional type may be em-

ployed.

ployed, made of a good quality of oil, admixed preferably with zinc oxide, white lead and calcium carbonate, and it is spread over the back face of the backing, which in application is then pressed against the wall.

By reason of the porosity imparted to the water soluble glue by its filler, the oil of the mastic will penetrate clear through such glue to the rear face of the glass or other rigid covering material and thus render such water soluble glue thoroughly waterproof. The casein type of glue is suitable as the bonding adhesive between the backing and the decorative covering, regardless of the character of the latter, whether its rear face be covered with paint, enamel, metal, metal foil or whether it be bare or uncoated.

Instead of the casein as the adhesive ingredient of the glue, liquid silicate of soda sometimes known as "water glass" may be used where the rear surface of the hard decorative covering is bare or uncoated. The liquid silicate of soda glue would be admixed with filler of calcium carbonate, lithopone, titanium oxide, clay or the like, just as with the casein glue, and would be applied in the manner above described. The liquid silicate of soda appears to have some etching effect on glass and would, therefore, not be used with transparent or translucent glass, but its use would be recommended where the glass, devoid of any coating on its rear surface, is opaque or nearly opaque or opaline in character, so that any such slight etching effect would not be visible through the exposed face of the glass. The decorative rigid cover plate 10 is, of course, converted into a panel assembly by any desirable method of cutting the plate into tiles or units, for instance, as disclosed in my prior patents referred to.

The backing of the embodiment disclosed in Figs. 1 and 2 has adequate compressibility to conform to the minor irregularities in the wall structure and yet when compressed by force exerted against the hard decorative material presents a relatively flat front face for the substantially mathematically plane rigid back of the latter. The backing also affords yield under shock, vibration or expansion between the front face thereof to which the hard front panel is affixed and the rear face at which it is secured to the wall.

In the embodiment of Figs. 3 to 6 the decorative covering is in the form of a panel of tiles 20 similar to those disclosed in my prior patents above identified, said tiles being desirably square or rectangular in form. The backing in this embodiment is made of any of a wide variety of woven fabrics, the weft and warp strands of which are however in bias relation with respect to the joints or edges of the tiles. Said strands 21 and 22 respectively as shown, desirably extend at an angle of 45° relative to the tile joints or edges 23. While any of a wide variety of woven fabrics is suitable for the intended purpose it is generally preferred to use swanskin or canton flannel which is a cotton fabric having a substantial nappe 24 on one or both of its faces.

The tiles are desirably attached to the backing of this embodiment by the same water soluble cement used in the embodiment of Figs. 1 and 2, so as to maintain the dry soft capillary character of the nappe exposed at the rear and thereby afford a large superficial area of contact with respect to the mastic used for securing the covering to the wall.

While the tiles may be individually applied, it is ordinarily preferred to secure a continuous

panel of glass or similar hard material to the face of the backing material and thereupon to cut such panel into the tiles as described in my prior patents above-identified.

As hereinbefore already indicated, I intend to include in my designation of hard decorative facing material, all such materials as exhibit the characteristics and properties making them suitable for the purposes of the present invention. I particularly mean to include such materials as synthetic resins of which the decorative tiles may be constituted. When using such materials, the individual tiles may be produced by cutting and grinding in substantially the same manner as the panels of glass. For instance, after a large size sheet has been attached to the supporting fabric, the plate may be broken along lines delineating the individual tiles, such lines having been imparted to the plate in the course of fabrication of such plate.

By reason of the bias relation set forth of the backing strands 21 and 22 with respect to the edges or joints of the tiles, the length of strands intervening between adjacent edges 23' and 23" of contiguous tiles is over 40% greater than if the strands ran parallel to the edges of the tiles.

To that extent, at least, the distendability of the fabric is enhanced (even disregarding the inherent extensibility of the threads), since the strands may under tension be displaced in the gaps between the tiles to substantial parallelism with the tile joints and this will occur without impairing the security of the bond of the individual tiles with respect to the backing.

Such distention of the panel will be uniform at the various parallel joints between the rows of tiles making up the panel so that the decorative appearance of the installed covering will not be impaired as it would be were the spacing between tiles rendered non-uniform by any such distention.

In Fig. 6 is clearly shown the mode of relative displacement of rows of tiles, to involve both relative separation and relative longitudinal shifting as suggested by the arrows. As appears in this figure, when the panel is distorted, the strands in the interval between adjacent tiles change their inclination relative to those portions thereof that are rigidly affixed to the surfaces of the tiles. The desired relative separation or longitudinal displacement of the tiles is thus effected, without loosening of the tiles from their backing.

In addition to the adaptability just set forth, it will be noted that by reason of the relatively thick-napped character of the canton flannel or similar material used, the same has felting characteristics to permit compression for conformation to irregularities or waviness in the wall structure.

In the embodiment of Figs. 7 to 10 the backing material 30 may be of paper, desirably of kraft paper. This paper is prepared with perforations 31 extending in longitudinal and transverse rows, the respective rows being spaced to circumscribe the various areas of tile to be affixed thereon. As shown in Fig. 7, perforations 31 are exposed in the intervals 32 between adjacent tiles and are desirably distributed also over the face of the tiles themselves. The backing disclosed is of course not distensible, but by reason of the substantial spacing between adjacent tiles, adjustment with respect to irregularities in the wall can be effected by partly closing up the gaps between the

tiles, the perforated paper ridges forming minute folds as at 33 between adjacent tiles. The mastic 34 penetrates through the apertures 31 in the application to the wall and fills the intervals between adjacent tiles, the mastic also penetrating through apertures 31' in the back of the tiles for enhanced security of mount thereof upon the wall.

A desirable method for fabricating the decorative covering embodiment of Fig. 7 is shown in Figs. 8 and 9. According to this embodiment a platform 40 is employed with a series of parallel longitudinal grooves 41 transversed by a corresponding series of transverse grooves 42 determining rectangular areas corresponding to the sizes of tile. The backing of strong paper such as kraft paper or the like is laid upon the platform with respective lines of perforations 31 preferably, but not necessarily, aligned with the troughs of the grooves and the backing material is pressed, as for instance by means of a ribbed die 43 to extend in fold lines along such perforations into the recesses of the respective grooves. The lines of perforations 31, if aligned with the troughs of the grooves, enhance the penetration of the mastic to the spaces between adjacent tiles, but equally good results are secured without the necessity of aligning such perforations to be immediately below the grooves. A flat continuous panel 44 of glass or other hard decorative material is adhesively secured to the exposed face of the backing mounted in the manner set forth in connection with the embodiment of Figs. 1 and 2, and shown in Fig. 9. Thereupon the panel is cut with a beveling tool, if desired, longitudinally and transversely at 45 along the lines determined by grooves 41 and 42, to divide the same into the desired tiles. Upon removal from the platform of the structure thus prepared and distending the same to flatten out the folds of backing material that had entered the grooves 41 and 42, the tiles will become separated longitudinally and transversely, resulting in the product shown in Fig. 7 and previously described.

While a backing of paper or like material of close texture, and desirably of some capillarity has been illustratively shown, it will be understood that other backing materials of low cost may be applied by the method shown in Figs. 8 and 9. Where material of open texture or open mesh such for instance as muslin is employed, additional perforations such as those at 31 are not required.

While in the embodiment of Figs. 1 and 2, the backing material has been shown applied to a continuous or uninterrupted rigid panel facing and therefore would not be subjected in the course of installation to longitudinal or transverse distension, it is to be understood that the backing material shown in Figs. 1 and 2, if made of a sufficiently good quality of fiber for uniform distensibility, could be used advantageously as the backing for a covering structure such as that shown in the tiled embodiment of Fig. 3.

The water soluble glue herein specified for attaching the decorative rigid facing to the flexible backing, and the water-proof mastic specified for securing the backing of the article to the wall cooperate to particular advantage where they are used in connection with the combination set forth and claimed in my prior Patent No. 1,976,986, reissued December 5, 1939, as Re. No. 21,285. Where the loose texture backing

material of tricot or the like specified in said prior patent is employed, the water-proof mastic will completely permeate and penetrate the backing as the covering material is applied to the wall, and will even penetrate through the water soluble glue and render entirely water-proof the bonding between the backing and the rigid facing.

My novel decorative material has a very extensive practical application for use in exteriors, for instance, as store fronts and the like, where it is subject to the elements. A substantial waterproof installation is secured by reason of the permanent character of the bond between the decorative material and backing on the one hand, and between the composite decorative coating and the surface to which it is applied by mastic, on the other hand, such bonds being capable of withstanding not only the ordinary effects of rain, sleet, and snow, but the influence of other atmospheric constituents that may be produced by gases, fumes, and vapors, whether alkaline or acidic.

As many changes could be made in the above construction and many apparently widely different embodiments of this invention could be made without departing from the scope of the claims, it is intended that all matter contained in the above description or shown in the accompanying drawing shall be interpreted as illustrative and not in a limiting sense.

Having thus described my invention, what I claim as new and desire to secure by Letters Patent is:

1. A decorative covering structure adapted to be directly secured to a wall or other surface, comprising a plate of rigid material and a flexible backing sheet to which said plate is glued by water soluble cement, said plate being constituted of a multiplicity of spaced units in jointed relation, said backing sheet being inherently of small distensibility longitudinally and transversely thereof and having exposed portions thereof extensible longitudinally and transversely in the regions between neighboring edges of adjacent units, to a sufficient degree to permit elongation of the covering structure and corresponding separation between adjacent units.

2. A decorative covering structure adapted to be directly secured to a wall or other surface comprising a rigid plate and a flexible backing sheet to which said plate is glued, said plate being constituted of a multiplicity of units in jointed relation, said backing comprising a flexible woven fabric, the various strands longitudinally and transversely of said fabric extending on the bias with respect to the edges of said units, said units throughout the rear surfaces thereof being rigidly secured to said fabric, whereby, by reason of the bias direction of the strands the covering may be distended to a substantial degree in the direction of the unit edges.

3. A decorative covering structure adapted to be directly secured to a wall or other surface, comprising a rigid plate and a flexible backing sheet to which said plate is glued, said plate being constituted of a multiplicity of units in jointed relation, said backing sheet being of flexible but substantially non-distensible material, the backing material having folds intermediate the neighboring longitudinal and transverse edges of adjacent units, whereby to afford extra length in said non-distensible backing material to permit slight change in the course of installation in the spacing between adjacent units.

4. The method of fabricating and installing a

decorative surface covering of the type including a flexible fabric backing having hard decorative facing tiles thereon, which consists in spreading water soluble glue with porous filler in an aqueous carrier upon the rear surface of the facing material, laying the fabric thereover and drying the assembly under heat, whereby the water constituent of the glue that penetrates the backing fabric is evaporated, leaving said fabric clean, supple and porous save for the outer surface 10

thereof that adheres to the facing, applying waterproof mastic to the rear face of the backing and pressing the covering against the surface to be covered, whereby the mastic will penetrate the backing as well as the porous water soluble glue at the outer face thereof, thereby rendering waterproof the fabric of the backing as well as the water soluble glue thereon.

GASTON DESAGNAT.
